(57) CLAIM

The ornamental design for an urban closet for advertisement, as shown and described.

DESCRIPTION

FIG. 1 is a perspective view of an urban closet for advertisement with one door open showing my new design; FIG. 2 is a side elevation view thereof, the opposite side view is mirror image thereof; FIG. 3 is a front perspective view thereof; FIG. 4 is a rear perspective view thereof; FIG. 5 is a top plan view thereof; and, FIG. 6 is a front elevation view with the door closed. The broken lines shown on FIGS. 1-6 are for illustrative purposes only and form no part of the claimed design.
